Primary Examiner — Cynthia Underwood(74) *Attorney, Agent, or Firm* — Davis Wright Tremaine LLP; George C. Rondeau, Jr.(57) **CLAIM**

The ornamental design for a locking swivel hook, as shown and described.

DESCRIPTION

FIG. 1 is top left side perspective view of a locking swivel hook showing my new design.

FIG. 2 is a left side elevational view thereof.

FIG. 3 is a right side elevational view thereof.

FIG. 4 is a front elevational view thereof.

FIG. 5 is a rear elevational view thereof.

FIG. 6 is a top plan view thereof; and,

FIG. 7 is a bottom plan view thereof.

The broken lines represent portions of the locking swivel hook that form no part of the claim.
